UNITED STATES PATENT OFFICE.

CURT WILLIBALD ALEXIS HANNEBOHN, OF BERLIN-CHARLOTTENBURG, GERMANY,
ASSIGNOR TO ALEXIS KELLNER, OF BERLIN-CHARLOTTENBURG, GERMANY.

MOTOR-CARRIAGE BODY.

Application filed January 10, 1925. Serial No. 1,680.

To all whom it may concern:

Be it known that I, CURT WILLIBALD ALEXIS HANNEBOHN, a citizen of the German Republic, and resident of Berlin-Charlottenburg, Germany, have invented a new and useful Improved Motor-Carriage Body, of which the following is a specification.

My invention relates to a motor-carriage body having two doors on each of its two sides and a common axle-forming column or standard for each pair of doors, the arrangement being such that the two doors connected with one another in this manner can be turned towards one another. Each door is provided in known manner with vertically turnable window guides which move together with it when it is opened or closed. When the carriage is completely closed and the doors are also closed, it is necessary to provide a good weather-proof joint between the up-standing window guides, and it has already been proposed to provide the guides with packing ledges on their back-faces.

In the customary construction, in which each door is pivoted to the common standard by an individual pair of hinges, the packing ledges necessarily must be made of soft rubber in order to permit opening of the doors when the window guides are in the vertical position, the ledges moving past one another because of their yieldingness. Packing ledges having projections and grooves engaging each other or rabbets could not be used for the motor-carriage bodies as devised hitherto, as the opening of only one of the two doors on either side of the carriage body would then be impossible. The use of rubber entails the drawback that the packing ledges become useless after a comparatively short time which is due partly to influences of the weather and partly to the frequent opening and closing of the doors. The rubber packing ledges must be replaced, therefore, by new ones after a comparatively short time, whereas packing ledges operating with feather and groove or with rabbets do not suffer from the drawback stated.

The object of my invention is to render possible the employment of these latter packing members in connection with the doors of motor-carriage bodies, it being understood that I have in view motor-carriage bodies with two doors on either side. For this purpose I hinge the two doors to a

common standard or column arranged somewhat outside the carriage body and being carried by it by suitable means, as described hereinafter by way of example.

My invention is illustrated by way of example in the accompanying drawing in which Figure 1 is a side-view of a completely closed motor-carriage; Figure 2 shows this carriage in open state; Figures 3 and 4 are horizontal sections in the plane A—B of Figure 1, these figures being drawn to an enlarged scale and Figure 3 showing the doors closed, Figure 4 open.

On the drawing *a* denotes the carriage body and *b*, *c* are its doors; they are hinged by hinges *d*, *e* to a common vertical standard or column *f* on which each of them may be turned independently of the other. The standard or column *f* is located at some distance from the outer face of the carriage body and supported by arms *t* projecting forth from said outer face.

The doors *b*, *c* enclose, as usual, the windows *g*, *h* which are held by vertical members *i*, *i'* and *k*, *k'*. These members are bipartite, and their upper parts are connected with the lower ones by hinges, so that the upper parts can be swung into vertical position, or folded down upon the spaces provided in the doors for the reception of the windows when the carriage is to be used in open state. *n* denotes the top or hood of the carriage body; it is shown in Fig. 1 in closed state and in Fig. 2 in open state.

Those faces of the members *l* and *m* which are located opposite one another when they stand upright are provided with separate tightening ledges *o* and *p*, of which *o* is provided with a groove *q* of semi-circular section, and *p* is provided with a correspondingly shaped feather *r* which engages the groove *q* when the parts in question are in the position shown in Fig. 3. The parts *o*, *q* on one side and *p*, *r* on the other side form together a tight closure preventing effectively the entrance of air into the completely closed carriage body.

The members *l*, *o* and *m*, *p* together may, in upright position, be employed as a supporting column for the roof or hood; they themselves are supported in this position by the vertical member *s* (Fig. 4) which is located between the body spaces receiving or containing the doors *b* and *c*. The arms

t carrying the hinges *d* and *e* project forth from said members *s*.

Either door on either side of the carriage body can be opened entirely independently 5 of the other door on the same side without any clamping or other interference of either the tightening member *o*, *q* or the tightening member *p*, *r*.

I claim:

10 In combination with a motor-carriage body having two doors on either side: two hinges located at some distance from the lateral faces of the carriage body, one on one side, the other on the other side of said body and each being adapted to serve for

the two doors of the respective side; bipartite window-guides on the doors the upper halves being hinged to the lower halves and adapted to be turned into horizontal and into vertical position; and tightening ledges 20 attached to the back faces of those window-guides which are located opposite one another when in upright position, one of the tightening ledges on either side of the carriage body having a longitudinal recess and 25 the other having a corresponding projection adapted to engage said recess.

In witness whereof, I have hereunto signed my name.

CURT WILLIBALD ALEXIS HANNEBÖHN.
